UNITED STATES PATENT OFFICE.

KARL KLIMPKE, OF BRAUNSCHWEIG, GERMANY.

CENTRIFUGAL SEPARATOR FOR PULPY MATTER SUCH AS GROUND WOOD OR STRAW,
CELLULOSE, AND THE LIKE.

Application filed August 2, 1923. Serial No. 655,382.

To all whom it may concern:

Be it known that I, KARL KLIMPKE, a citizen of Austria, residing at Braunschweig, Germany, have invented certain new and useful Improvements in Centrifugal Separators for Pulp Matter Such as Ground Wood or Straw, Cellulose, and the like (for which I have filed applications in Germany August 14, 1922, and Austria 10 June 30, 1923), of which the following is a specification.

My invention relates to improvements in centrifugal separators for pulpy matter such as ground wood or straw, cellulose, and the like, and more particularly in separators of the type in which the matter to be separated is supplied into a drum having its circumferential wall in the form of a sieve and comprising a rotary member provided with 15 blades throwing the matter against the circumferential sieve. In one type of apparatus of this class the matter flows into the sieve in the form of a single current, and in another type it is discharged through a plurality of openings, so that it is uniformly distributed over the area of the sieve. The object of the improvements is to provide an apparatus of this type in which the matter is uniformly distributed over the area of the 20 sieve, and in which obstruction of the discharge by the matter is avoided. With this object in view my invention consists in constructing the discharge in the form of one or two overflows open at the top and extending substantially over the whole length of 25 the drum. Preferably the overflow or overflows are subdivided by ribs into a plurality of sections each in the form of a channel which is open at its top, and the channels 30 extend to different parts of the circumference of the drum.

For the purpose of explaining the invention an example embodying the same has been shown in the accompanying drawing, 35 in which the same letters of reference have been used in all the views to indicate corresponding parts. In said drawing,—

Fig. 1, is an elevation of the separator, the sieve and the cylindrical wall enclosing the same being shown in section to illustrate 40 the distributing member,

Fig. 2, is a longitudinal section of the separator,

Fig. 3, is a cross-section of the sieve, the rotary blades, and the distributing member 55 taken on the line 3—3 of Fig. 2,

Fig. 4, is a similar cross-section taken on the line 4—4 of Fig. 2, and

Fig. 5, is another section taken on the line 5—5 of Fig. 2.

In the example shown in the figures my improved separator comprises a pair of end plates a^1 and a^2 mounted on a suitable foundation, a cylindrical wall b connecting the same, a cylindrical sieve g secured to annular shoulders g^1 of the end walls, a shaft c mounted in bearings d and carrying fixed and loose pulleys h and h^1 , a wheel f carrying blades f^1 and keyed to the shaft c , and a distributing member e within the sieve and 60 having an inlet e^1 . The end wall a^2 is formed with a discharge i communicating with the inner part of the sieve, and the cylinder b is provided with a discharge j communicating with the annular chamber provided between the wall b and the sieve g .

The distributing member e is in the form of a trough which is open at its top so as to provide two overflows k extending substantially over the whole length of the trough 65 and disposed at the same level. The trough is formed with circumferential depressions l^1 , l^2 , l^3 , and l^4 , l^5 so as to provide channels separated by ribs n and extending downwardly to different heights indicated by the 70 letters m^1 , m^2 , and m^3 .

In the operation of the apparatus the semi-liquid or pulpy matter is passed into the distributor e and it fills the same up to the overflows k , so that the matter is uniformly discharged over the whole length of the distributor, and the stream of the matter is divided into the channels l^1 , l^2 , l^3 , said 75 channels having the functions, first to prevent the parts of the stream to be again combined into a single stream, and second to direct the matter to different parts of the circumference of the sieve g . As shown the bottoms of the channels are curved outwardly at their discharge ends, so that the 80 matter discharged from the channels flows outwardly and towards the blades which

throw the same against the sieve. Therefore the mass of the matter is uniformly distributed over the whole circumference of the sieve. By providing overflows which are open at their tops the discharges can not be obstructed by the matter even if a large amount thereof is discharged.

While in describing the invention reference has been made to a particular example embodying the same, I wish it to be understood that my invention is not limited to the construction shown in the drawing, and that various changes may be made in the general arrangement of the apparatus and in the construction of its parts without departing from the invention. For example I do not limit myself to a construction in which a single distributing member is provided, or in which the mass of semi-liquid or pulpy matter is broken up internally of the sieve *g*. In some cases I divide the matter outside the sieve into separate streams and I conduct the same to separate overflows provided within the sieve *g*.

25 I claim:

1. In an apparatus of the class described, the combination, with a sieve, and a rotary member mounted on a substantially horizontal axis and adapted to throw the matter to be separated against the sieve, of distributing means for supplying the matter to be separated to the rotary member and having an open overflow for the discharge of the matter to the rotary member, said overflow being divided into sections adapted to divide the matter being discharged into separate streams.

2. In an apparatus of the class described, the combination, with a sieve, and a rotary member mounted on a substantially horizontal axis and adapted to throw the matter to be separated against the sieve, of distributing means for supplying the member and having an open overflow for the discharge of the matter to the rotary member, said overflow being divided into sections in the form of channels ending at different

parts of the circumference of the sieve and adapted to divide the matter being discharged into separate streams.

3. In an apparatus of the class described, the combination, with a sieve, and a rotary member mounted on a substantially horizontal axis and adapted to throw the matter to be separated against the sieve, of distributing means for supplying the matter to be separated to the rotary member and having an open overflow for the discharge of the matter to the rotary member, said overflow being divided into sections in the form of channels ending at different parts of the circumference of the sieve and adapted to divide the matter being discharged into separate streams, the bottoms of said channels being directed at their discharge ends outwardly and towards the rotary member.

4. In an apparatus of the class described, the combination, with a sieve, and a rotary member mounted on a substantially horizontal axis and adapted to throw the matter to be separated against the sieve, of a distributing trough having an open overflow at its top for supplying the matter to be separated to the rotary member, said overflow being divided into sections in the form of channels disposed circumferentially of the trough.

5. In an apparatus of the class described, the combination, with a sieve, and a rotary member mounted on a substantially horizontal axis and adapted to throw the matter to be separated against the sieve, of a distributing trough having an open overflow at its top for supplying the matter to be separated to the rotary member, said overflow being divided into sections in the form of channels disposed circumferentially of the trough and ending at different parts of the circumference of the trough.

In testimony whereof I have affixed my signature.

KARL KLIMPKE.
